UNITED STATES PATENT OFFICE.

GEORGE X. WENDLING, OF SAN FRANCISCO, CALIFORNIA.

LUG BOX.

Application filed August 17, 1922. Serial No. 582,357.

To all whom it may concern:

Be it known that I, GEORGE X. WENDLING, a citizen of the United States, residing at the city and county of San Francisco 5 and State of California, have invented certain new and useful Improvements in Lug Boxes, of which the following is a specification.

Due to the high cost and scarcity of good 10 lumber, free from sap, and light in weight for the making of shipping boxes particularly adapted for shipping fruit, I have conceived the idea of manufacturing a light weight, strong and cheaply constructed box 15 from narrow, relatively thin and short lengths of material. By the manufacture of a box from this thin veneer like material I am able to use material heretofore not adapted for box making, and by such use I 20 conserve the forests and use to advantage lumber heretofore discarded in the scrap pile.

My improved receptacle or shipping box due to the connecting of the spaced strips 25 of the respective walls at their ends by cleats, and due to the uniting of the cleats to the ends of the strips by staples, the bridles of which are disposed across the grain of the wood, rigid wall members are 30 provided which are adapted for securing to the box ends preferably by nails passing through the ends of the strips and cleats. To afford a reinforcement for the top or cover of the box or receptacle, a lug or 35 batten is secured to the upper edge of each end to extend longitudinally thereof and overhang the inner face of the corresponding ends. This affords a firm support for the cover and prevents the sagging thereof 40 when the receptacles are arranged in stack formation, and prevents the terminal side edges of the cover from engaging with the terminal side edges of the opposing side walls overcoming the pinching of the con- 45 tents of the box therebetween.

With the above mentioned and other objects in view, the invention consists in the novel construction and combination of parts hereinafter described, illustrated in the accompanying drawings, and set forth in the claim hereto appended, it being understood that various changes in the form, proportion, size and minor details of construc-

tion within the scope of the claim may be resorted to without departing from the 55 spirit or sacrificing any of the advantages of the invention.

To more fully comprehend the invention, reference is directed to the accompanying drawings, wherein:—

Figure 1 is a view in broken perspective of the preferred embodiment of my invention.

Figure 2 is a vertical sectional view of two of the receptacles arranged in stack 65 formation.

Figure 3 is a fragmentary end view illustrating the arrangement of the cleat, staple, and batten or lug, and

Figure 4 is a sectional view through one 70 of the cleats and strips illustrating the clinching of the securing staple.

Referring more particularly to the several views of the drawings wherein like characters of reference designate corresponding parts, 1 indicates a box or receptacle end members disposed in parallel relation, and to their upper edges are secured the lug or batten strips 2 which extend longitudinally thereof with their inner edges 80 overlying opposing faces of the end members 1 as at 3. The lugs or battens are preferably secured in position by nails or other securing means 4. Side walls 5, a bottom wall 6 and a top wall 7 connect the 85 opposing ends 1, and each of said walls consists of a plurality of relatively thin narrow parallel spaced veneer-like strips of wood 8, the grain of which extends longitudinally of the strip. These strips before the walls 90 are secured to the box ends are arranged in parallel relation, and across the ends thereof are disposed the transverse cleats 9. Staples 10 are then forced through the cleats and strips with their spirals 11 disposed across the grain of both the cleat and the strip preventing the splitting of the wood and insuring a secure union. The terminal ends of the staples are clinched as at 95 12 to prevent the same from becoming loose. After the walls are assembled, they are positioned in place and are secured to the box ends by nails 13 or other securing means.

It will be observed that the overhanging flange or portion 3 of the lug 2 serves as a 100 support for the cover and also remains in

position on the box after the cover is removed.

In constructing this box or receptacle, it will be observed that the usual method of 5 constructing wooden boxes is departed from, and that each wall is assembled from a plurality of strips to form a union, and is afterwards secured in position.

It will be readily understood that this 10 box is capable of being manufactured at the factory i. e. sides, top and bottom, formed in the requisite sizes and shipped with the ends in a knocked down condition to the user, who after receiving the units may 15 readily assemble the box by driving a comparatively few nails.

In constructing a box of slats and cleats, the cleats being relatively narrow in width, it will be readily apparent that material 20 imperfect for use as slats may be worked into cleats, thereby reducing the waste of material to a minimum.

Having thus described my invention,

what I claim as new and desire to secure by Letters Patent of the United States is:— 25

A box comprising a pair of spaced end members, a pair of lugs one extending longitudinally of corresponding edges of each end member and projecting inwardly beyond adjacent faces of said end members, 30 side, top, and bottom walls for said box and connecting said end members, said walls each comprising a plurality of relatively thin, narrow, parallel spaced strips, a cleat extending transversely of opposite ends of 35 the strips of the respective walls, staples passing through said cleats and strips and clinched at their ends to unite the parts, the staples being disposed with their bridles across the grain of the strips and cleats, and 40 means passing through the strips and cleats for securing the opposite ends of the respective walls to their respective box ends.

In testimony whereof I have signed my name to this specification.

GEORGE X. WENDLING.
